(57) CLAIM

The ornamental design for a lunch box, as shown and described.

DESCRIPTION

FIG. 1 is a perspective view of a lunch box showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof;

FIG. 8 is an enlarged view of the encircled area 8 of FIG. 3; and,

FIG. 9 is an enlarged view of the encircled area of FIG. 3. The dot-dash line in FIGS. 3, 8, and 9 which define the bounds of the claimed design form no part thereof. The broken line rectangular boxes identifying the enlarged views shown in FIGS. 3, 8, and 9 form no part of the claimed design. The remaining broken lines shown in the figures depict portions of the lunch box that form no part of the claimed design.
